ICE AND SNOW SKATE

Gottlieb Trächslin, Basel, Switzerland

Application November 28, 1944, Serial No. 565,531
In Switzerland December 3, 1943

5 Claims. (Cl. 280—11.13)

1

This invention relates to snow and ice skates to be attached to shoes, mainly composed of an intermediate runner connected with a supporting surface projecting on each side, whereby the supporting surface and also the runner projecting therefrom in a downward direction are uniformly bent upwards in the front part, the head of the skate being provided with a downwardly effective device for the forward movement of the skater. The width of the running surface of the runner should advantageously and approximately correspond with that usually employed in ice skates and, at most, it should only project out of the supporting surface to an extent corresponding with its width.

According to the present invention, it is possible to run on ice and on snow. When skating, merely the runner takes effect. In this case, there is no principal difference, as compared with skating by means of skates usually employed. However, in the case of snow, the runner takes a cutting effect. Therefore, the supporting surface is located on the snow in such a manner that extensive sinking into snow is prevented. However it is possible to run on a surface of snow, due to the supporting surface being upwardly bent in its front part, similarly to the pointed end of a ski. If the supporting surface is formed in such a manner that each half of the supporting surface has an outwardly rising form, the supporting part of the supporting surface will automatically, according to the consistency of the snow, adapt itself to the existing relation of force, inasmuch as, in the case of hard snow, only a more or less narrow zone of the supporting surface on both sides of the runner lies on the snow, whereas the outer zones of the supporting surface project above the snow.

It is an object of the present invention to provide each half of the supporting surface in a form which resembles that of a vault or arch. It is also possible to provide a supporting surface of a shape which in cross section has the general form of the letter V. The above mentioned shapes are not only advantageous when the skate is used for running on snow, but also for skating on ice, because the upwardly curved supporting surface does not, in any way, interfere with the setting on edges, when running along curves on ice. In other words, the outer edges of the supporting surface will not contact the ice surface when the skate is tilted as it is usually done when running along curves. The ice and snow skates hitherto known have straight or plane rather than curved or arched supporting surfaces

so that said known skates have the disadvantage that their supporting surfaces contact the ice surface when the skater runs along curves on ice. Another advantage of the vaulted or curved supporting surface over a straight or plane supporting surface in this type of skates is that the skate when used for running on snow penetrates the snow only to the extent necessary to support the weight of the skater, while straight or plane supporting surfaces always contact the snow surface with their entire area.

The supporting surface may be composed of an integral piece, the runner then being advantageously attached to its lower side. Instead of this construction, each half of the supporting surface may be made of a separate piece. In this case, each half of the supporting surface will be attached to one side of a traverse, which either carries the runner on its lower part, or is formed as a runner. Each half of the supporting surface may be subdivided, composed of two or more longitudinally directed single strips. They may be arranged at a certain distance from each other, and they should advantageously be held by a mutual support. These strips may have a curved form, whereby the entire supporting surface would be composed of runners positioned at a certain distance from each other and directed longitudinally, whereby these runners are located symmetrically with respect to the central runner.

The accompanying drawings show, by way of illustration, an example of the present invention in which

Fig. 1 is a longitudinal sectional view of the skate,

Fig. 2 is a top plan view,

Fig. 3 is a cross section through the rear boot-attaching device, taken on line A—B of Fig. 1.

According to Figs. 1 and 2, *a* represents the central, longitudinal portion of the supporting surface, *b* designates the runner mounted thereon which is approximately as high as the width and projects downwardly from the supporting surface. As shown at the left of Figure 1, the front portion of said runner *b* is curved upwardly in the same manner as the supporting surface *a*. Just in front of the point of transition of the substantially straight runner portion and the curved runner portion, the runner edge is provided with downwardly directed dents or teeth *b*, which provide for gripping action on ice. An edge-part *a* is located adjacent to each side of the central supporting surface *a*. This edge-part is attached to the central part *a* by means of screws or rivets *a*. The central sup-

porting surface a_1 is vaulted upwardly, while the adjoining edge parts a_2 are substantially horizontal, as viewed in the cross-section of Figure 3. In the longitudinal direction of the skate, the central and rear portions of the edge parts a_2 are substantially horizontal. At the front portion, however, the edge parts are upwardly bent, as they substantially correspond to the curvature of their central supporting surface a_1 . The edge parts may be made of wood, or artificial material, or of metal, in particular sheet metal. They may be made of one piece with the supporting surface.

The head-part a_6 is provided with a device for forward movement, this device being composed of 2 steel ledges c_1 and c_2 . The steel ledge c_1 , as shown in Fig. 2, is only provided across the central flat bent part a_7 of the head of the device, whereas the second ledge c_2 , positioned in front thereof, is provided with flanks projecting beyond it, which, in horizontal section, show a curved form c_6 with a sharp turn c_8 towards the rear. Both ledges are mounted on the supporting surface by means of screws c_3 screwed in the front rim or edge of said supporting surface. The ledge c_1 is provided with sharp, downwardly directed dents or teeth c_4 , whereas the ledge c_2 shows a sharp lower edge of thin steel plate. Therefore, any further sharpening is not required. Directly behind the device for the forward movement, the supporting surface, and particularly its central part a_1 on both sides of the runner b , is provided with apertures a_4 . Their object is to prevent accumulation of snow, inasmuch as evidently, as shown in Fig. 1, snow could be squeezed into the acute-angled corner between the central supporting surface a_1 and the ledge c_1 for the forward movement, when the device for the forward movement is set into action. By means of these apertures a_4 , snow is permitted to break its way through upwardly, whereby it is automatically discharged.

The rear part of the supporting surface is developed or merges to a point a_9 , as shown in Fig. 2. This enables excellent running on snow, besides straight stepping and, furthermore, it facilitates steering possibilities. In order to reduce running resistance, the central supporting surface a_1 is provided with streamlined indentations a_5 in the front bend, whereby the form of these indentations should be selected according to streamlined requirements. The indentations have resistance-reducing properties similar to the indentations in the bows of ships on both sides of the keel-line.

The device for the attachment of boots is composed of a front a_{10} and a rear part a_{11} , similar to skates. The front part serves for the reception of the boot-sole, the rear part for that of the heel. For this purpose, tin or sheet metal plates d_1 are provided which, by means of the angle pieces d_2 , rest on the central supporting surface a_1 , screws or rivets d_3 mounting the plates d_1 on the angle pieces d_2 . Angular clamps d_4 , as used in conventional skates, are supported in sliding guides d_5 on each side of said plates d_1 , capable of being laterally inserted and pushed out. They are arranged to project downwardly into the supporting angle pieces d_2 and are provided with a female screw thread, with which they run on the fixing bolt d_6 , provided on one side with a square portion d_7 , capable of being engaged and turned by a regular key. The screw is supported in the central counter part d_8 , which is attached to the plate d_1 by means of rivets.

The use of this new skate is readily apparent from the foregoing description. By attaching a skate to each boot the usual technical skill is applied as with conventional skates. The shape of the runner corresponds to that of the conventional skates. The dents b_1 for gripping action on ice and the devices c_2 and c_4 for gripping action on snow facilitate the forward movement. The rear end of the runner (see Figure 1) may be used as a brake, as it is adapted to cut into the ice with sharp edges. If snow conditions are favorable, the ledge c_2 may be used as brake. In this event, only the ledge c_2 becomes active, because only said ledge c_2 is pressed into the snow shoving the snow forward, when the boot is tipped for braking. When running on snow under normal conditions, the ledges c_2 and c_1 are above the snow surface. If the snow is very soft and loose, its consistency is decreased and the ledges c_2 and c_1 may somewhat penetrate the snow. However, the resistance of soft and loose snow is relatively small, so that the penetration of the ledges c_2 and c_1 into the snow does neither considerably brake the skate nor otherwise unfavorably affect its running qualities. The ends c_8 of the ledge c_2 are curved and directed towards the rear of the skate to decrease the resistance of the skate when said ledge c_2 contacts the snow. If the snow layer is hard, as in the case of old and frozen snow, the skate only sinks to a small extent, whereby the central supporting surface a_1 is partly fully pressed into the snow, the edge-parts a_2 , however, act as stabilizing surfaces and render safe running possible, especially when running curves.

It is obvious that various changes, substitutions and modifications may be resorted to without departing from the spirit and scope of the invention.

I claim:

1. In a snow and ice skate having supporting surfaces on each side of a runner, an ice and snow gripping device in the form of a downwardly projecting member secured to the supporting surface at the front part of and across the skate, said gripping device having a substantially straight central portion merging into adjacent, inwardly bent side portions which end into extremities directed towards the rear of the skate.

2. An ice and snow skate comprising a central runner, a supporting surface extending from each side of the runner, the runner projecting from the under surface of the supporting surface, means for securing the skate to a shoe, and an ice and snow gripping device secured to the front of the skate in the form of a downwardly projecting member extending around the front part of the skate to grip the ice and snow when the skate is tilted.

3. An ice and snow skate according to claim 2, in which a second downwardly extending member is secured to the front part of the skate in spaced relation with the first-mentioned projecting member.

4. An ice and snow skate comprising a central runner, a supporting surface extending from each side of said runner, the runner projecting downwardly from the supporting surface, said runner and supporting surface being upwardly bent in their front part, and a downwardly projecting device at the front of the skate to grip the ice and snow and positioned transversely relative to the runner, said projecting device being composed of a central, substantially straight front

portion and adjacent lateral flanges which are bent towards the rear of the skate.

5. An ice and snow skate according to claim 4, in which the supporting surface is provided with a perforation on each side of the runner at 5 the front just behind the projecting device.

GOTTLIEB TRÄCHSLIN.
